UNITED STATES PATENT OFFICE.

FRANK HEINIG, OF WINNETKA, ILLINOIS.

DESIGN FOR A CABINET.

SPECIFICATION forming part of Design No. 29,398, dated September 20, 1898.

Application filed July 18, 1898. Serial No. 686,292. Term of patent 14 years.

To all whom it may concern:

Be it known that I, FRANK HEINIG, a citizen of the United States, residing at Winnetka, in the county of Cook and State of Illinois, have invented a certain new and original Design for Cabinets; and I do hereby declare the following to be a full, clear, and exact description of the invention, such as will enable others skilled in the art to which it applies to make and use the same, reference being had to the accompanying drawings, and to letters of reference marked thereon, which form a part of this specification.

Figure 1 is a front elevation of a cabinet, showing my new design. Fig. 2 is an end elevation showing the same cabinet. Fig. 3 is a top plan showing the same cabinet.

As shown in the drawings, the leading or material features of my design consist of the equal parallel vertical faces A, longer horizontally than their height and rectangular at the bottom and converging at the upper por-

tion and separated from each other by a distance less than the length of said faces, the horizontal rectangular top face C, reaching from one face A to the other, the vertical rectangular end faces B, perpendicular to the faces A, and the horizontal faces B² and vertical faces B', each extending from one face A to the other and extending in alternation from the end faces B through an oblique plane upward to the top face C.

Having described my invention, what I claim as new, and desire to secure by Letters Patent, is—

The design for a cabinet, as herein shown and described.

In testimony whereof I affix my signature in presence of two witnesses.

FRANK HEINIG.
